UNITED STATES PATENT OFFICE.

BENJAMIN D. CURTIS, OF PHILADELPHIA, PENNSYLVANIA.

LUMBER DRIER.

1,407,786.

Specification of Letters Patent. Patented Feb. 28, 1922.

Application filed March 29, 1920. Serial No. 369,770.

To all whom it may concern:

Be it known that I, BENJAMIN D. CURTIS, a citizen of the United States, residing at Philadelphia, in the county of Philadelphia 5 and State of Pennsylvania, have invented certain new and useful Improvements in Lumber Driers, of which the following is a specification.

My invention has reference, more particularly, to a drier of the compartment type in which a quantity of lumber or other material is enclosed and subjected to heated air which is circulated therein so as to dry and season the lumber.

In drying lumber, it has been found that the drying is more effectively accomplished if the lumber is first subjected to a steaming treatment, as this opens the pores of the lumber and facilitates the emission of sap and moisture when the heated air is passed in contact with the lumber to dry and season same, and my invention, in addition to the drying facilities, also has provision for affording the desired preliminary steam treatment.

The principal objects of my invention are to provide an improved drying kiln adapted to afford effective recirculation of the air in the kiln to facilitate steaming or drying; to provide a drying kiln having an improved arrangement of selectively operable steaming and drying devices which may be automatically controlled; to enforce recirculation by controlled cooling of walls of the drying kiln; to automatically regulate the exhaust of air from the drying kiln; to provide means for indicating and recording the effect of the steaming and drying operations on the lumber so as to enable the proper extent of each operation to be readily determined; and in general, to provide an improved drying kiln of simple form and convenient to operate and use and provided with controlling devices whereby the drying and seasoning of lumber may be expeditiously and thoroughly accomplished.

On the drawings, Fig. 1 is a horizontal, sectional view through the drying kiln and the adjoining operator's room, said view being taken substantially on the line 1—1 of Fig. 2; Fig. 2, a transverse, sectional view through the kiln taken on the line 2—2 of Fig. 1; Fig. 3, a longitudinal, vertical, sectional view on the line 3—3 of Fig. 1; Fig. 4, an enlarged, fragmentary view of the damper for controlling the admission of air to the air

space in the side walls of the kiln; Fig. 5, an enlarged, fragmentary, sectional view on the line 5—5 of Fig. 1 showing the valve or door controlling the admission of air to the flue underlying the heating coils; Fig. 6, an enlarged, fragmentary, sectional view on the line 6—6 of Fig. 2; Fig. 7, a sectional view through the exhaust stack taken on the line 7—7 of Fig. 2; Fig. 8, an enlarged, fragmentary, sectional view on the line 8—8 of Fig. 2 showing the automatic dampers in closed position; Fig. 9, a sectional view on the line 9—9 of Fig. 8 with the side wall of the exhaust stack removed; Fig. 10, a detail view showing the application of the recording device to the lumber in the drier; Fig. 11, an enlarged face view of the recording device; Fig. 12, a detail view showing the adjustable connection of the recording lever with the adjusting cable; Fig. 13, an enlarged, fragmentary, sectional view on the line 13—13 of Fig. 3 showing the arrangement of heating coils; Fig. 14, a detail view of the top mounting of the adjustable hanger which supports the heating coils; and Fig. 15 a detail of the bottom mounting thereof.

Referring to the drawings, the reference numeral 1 indicates a rectangular foundation or footing upon which the walls of the drying compartment are built, the space enclosed by the footing being filled in to any suitable height, as indicated at 2, excepting where provision is made as hereinafter indicated for ducts and other openings. Extending lengthwise of the drying compartment between the side walls thereof is a pit 3 with side walls 4 which have rails 5 mounted on the top to support a car or truck 6 upon which the lumber is piled or stacked and transported into and out of the drying compartment. Girders 7, placed at suitable intervals, extend over the pit 3 and have their ends mounted in the side walls 4, and may have a center rail 8 thereon to furnish additional support for the truck 6.

The side walls of the drying compartment are composed of two separated sections 10 and 11, having an air space 12 therebetween, the inner section 11 being preferably somewhat thin so that the cooling effect of the air in the space 12 is communicated readily to the inner surface of the section 11. The wall sections 10 and 11 are connected together at the top so as to close the air space 12 except at suitable intervals where stacks, or flues, 13 project thereabove and afford ven-

tilation outlets for the air space 12. These flues are preferably covered by caps 14 leaving side openings 15 thereunder, as shown.

Air is admitted to the air space 12 through an opening 16 at the end of each side wall near the bottom thereof, each of which openings is regulated by a damper or door 17 sliding in upright ways 18 at each side of the opening and arranged in any suitable manner so that the door may be held in any position to which it is adjusted to regulate the admission of air to the air space 12. A grid 19 extends lengthwise of each wall 10-11 in the air space 12 at the level of or slightly above the top of the opening 16, the purpose of which is to afford even distribution of the air, entering through the opening 16, along the length of the wall 10-11 for passage up through the air space 12 so that the interior of the wall sections 11 will be uniformly cooled. This grid 19 may be of any suitable construction, as for example, a grid plate mounted in and extending between the wall sections 10 and 11, or may consist of a course of brick suitably spaced apart and tying the wall sections 10 and 11 together. The wall sections 10 and 11 may, of course, be tied together at other points, if desired, so long as the means employed does not interfere with the proper circulation of the air up through the air space 12.

The tracks 5 and 8 lead into the drying compartment at one end thereof and this end of the drying compartment has a large opening 20 provided with one or more doors 21 which permit a loaded truck to be inserted in or removed from the compartment. These doors, of course, completely close the opening 20 and seal up that end of the compartment during the drying operation. The other end of the compartment is closed by a solid wall 80 with, of course, the necessary openings for air or other inlets therethrough, and has an enclosure 81 at the outer side to afford an operator's compartment 82, in which valves and other mechanism for controlling the operation of the drier are arranged for operation. Obviously doorways leading into the compartment 82 and from this compartment to the drying chamber may be provided to suit the convenience. A roof 83 entirely closes the top of the drier compartment, and, like the walls of the drier, may be of any desirable construction so long as it is heat resisting and does not readily dissipate the heat in the drier compartment.

Extending along each side of the drier compartment adjacent to the side walls thereof and just below the floor line, is a large duct 84 which has a shield or cover plate 22 extending almost across the top thereof and with a wall 23 depending from the edge thereof almost to the bottom of the duct 84, so as to leave a narrow space 24

along the side wall of the drier through which draft circulation may take place from the drying compartment to the duct 84. The restriction of the passageway 24 serves to equalize the draft influence afforded by the draft duct, throughout the length of the side wall of the compartment and afford uniform circulation throughout the drying compartment. Each of these ducts 84 communicates at one end with a stack 25 which adjoins the wall 80, and the walls 22 and 23 terminate at the juncture of the duct 84 with the stack 25 so as to permit free exit of the air from the duct 84 into the stack. These stacks are extended up above the roof 83 a sufficient distance to afford the required ventilation and have ventilators 27 or other suitably capped outlets at their upper ends. Each stack 25 has a damper 28 mounted to slide therein in guides 29 and operable by a handle 30 projecting into the operator's room 82 so that the draft or exhaust of air from the flues 25 may be manually controlled or entirely interrupted.

A pair of dampers 31 and 32 are pivoted at opposite sides of each flue 25 and each is substantially one half the transverse area of the flue so that they come together in horizontal position and close the flue, as shown in Fig. 8. These dampers or valves are automatically controlled, or operated, by thermostatic devices arranged respectively at the exterior and interior of the drying compartment so that the draft through the flues 25 is regulated automatically, in accordance with the temperature inside and outside the drying compartment. The thermostatic devices which are indicated respectively at 34 and 35 are the same except as to the range of temperature within which they operate, and each comprises an expansible fluid container, (not illustrated in detail as such elements are well known) each of which is connected with a bulb containing thermo-sensitive fluid. The bulb 34^a which operates the element 34 is located outside the drying compartment and connected by the tube 34^b with the element 34 so that the latter contracts or expands in accordance with the temperature outside the drier, and the bulb 35^a which operates the element 35 is located inside the drying compartment and connected by the tube 35^b with the element 35 so that the latter contracts and expands in accordance with the temperature inside the drier.

A lever 36 is pivotally mounted at one end adjacent the element 34 on a bracket 37 and connected with the moving part of said element by a stem or in other suitable manner so that the lever 36 is caused to swing on its pivot as the element 34 contracts or expands. The outer or free end of the lever 36 is connected by the link 39 with a crank arm 40 on the pivot shaft 41 to which the valve 32 is secured, said shaft being extended out

through the side wall of the stack as indicated in Fig. 8 to enable the connection to be readily made. With this arrangement the lever 36 swings outwardly upon expansion of the element 34 and imparts an opening movement to the valve 32, the range of operation of the element 34 being preferably from 0° to 100° F. so that the damper or valve 32 is closed at a temperature of 0° F. at the exterior of the drying compartment and open at 100° F.

The element 35 preferably has a range of operation corresponding to the possible range of drying temperature in the drying compartment, as for example, from 100° F. to 200° F. and is connected with the valve 31 so as to operate reversely to the valve 32, that is, the valve 31 closes upon rise of temperature in the drier, whereas the valve 32 opens upon rise of temperature outside the drier.

The element 35 has a link and lever connection with the arm 42 of the valve 31 similar to the connection of the element 34 with the arm 40 of the valve 32 and the corresponding parts are similarly designated on the drawing. The arm 42, however, extends in a direction from its shaft 43 opposite to that of the arm 40 so as to effect opposite movement of the valves 31 and 32 by their thermostatic elements 34 and 35, and the shaft 43 is extended laterally through the side wall of the stack 25 to facilitate making the operating connection.

In the bottom of the pit 3 is a pair of flues 47, each of which extends from end to end of the drying compartment and has a top 48 with apertures 49 arranged to distribute the supply of air from the flues 47 throughout the length of the drying compartment. Each flue 47 opens out through the end wall 80 and the open end thereof is controlled by a valve 50 which may be adjusted and held in adjusted position in any convenient manner.

Each flue 47 is connected with the duct 84 at the corresponding side of the compartment by a number of spaced pipes 51 and the outer end of each pipe 51 in the duct 84 is controlled by a valve 52. All of the valves 52 in each duct are connected to a rod 53 mounted in sliding bearings and having a handle 44 in the operator's compartment 82 for adjusting the valves 52 to control draft circulation through the pipes 51.

The pit 3 is provided to accommodate steaming pipes and heating coils which extend from end to end of the drying compartment, the former being suspended in any suitable manner from the I-beam girders 7 and the latter being carried by and between the girders 7 and inverted channel beams 63 which extend across the pit 3 between the walls 4 near the bottom.

The steaming device comprises a pipe 55

running lengthwise of the pit 3 between the side walls which has branches 56 at the end connecting with return pipes 57 arranged respectively adjacent the walls 4 and connected at their terminal ends by booster pipes 58 to the inlet end of the center pipe 55. A plurality of pipes 59, perforated in their upper surfaces, are connected at intervals along the pipes 55 and 57 so as to exhaust steam upwardly over a large area and are preferably arranged in an angular relation to the pipes 55 and 57. These pipes 59 are located between the girders and elevated above the pipes 55 and 57, each of said pipes 59 being provided with a downturned connecting portion 86 to prevent water of condensation escaping through the perforations of the pipes 59. The pipes 55, 56 and 57 are sloped so as to drain to the ends of the pipes 57 and discharge the water through a drain pipe 61 and trap 86a. The inlet end of the pipe 55 is connected with the steam main 87 through a manually operable valve 88 and a temperature controlled valve 89, which latter is connected by the tube 90 with a bulb 91 in the drying compartment for automatically regulating the supply of steam by the temperature in the drying compartment.

The heating device consists of oppositely inclined batteries of steam coils 62 and 65 at opposite sides of the pit 3, each of which coils comprises a plurality of pipe lengths with the ends connected by return bends so as to form a continuous steam duct. The upper length of each of the coils 65 and 62 is connected with a cross pipe 92 which communicates through the valve 85 and temperature controlled valve 89 with the steam main 87, and the lower lengths of the coils 62 and 65 are connected with a cross pipe 93 which leads to a trap 94. It will be observed that each coil 62 or 65 is independent and the ends thereof are preferably connected with the pipes 92 and 93 through unions 94a and 95 respectively so that each coil may be independently removed for replacement or repairs. The coils 62 are mounted on hangers 96 which may be secured at their upper and lower ends respectively to the girders 7 and channel iron supports 63 by bolts or clamps, or in any convenient manner, and each of the coils 65 is preferably mounted for movement along the girders 7 and channel iron support 63 so as to permit access to be had to the various coils without removing same from the pit 3. This movable mounting of the coils 65 may be accomplished in any suitable manner, as for example, by providing the hanger 97 upon which the coil 65 is mounted with rollers 98 at the upper end engaging the lower flange of the girder 7 and a roller 99 at the lower end engaging the top of the channel iron 63.

For determining the extent of the steaming and drying upon the lumber in the dry-

ing compartment, I provide, preferably in the operator's room 82, a recording instrument 66 which comprises an operating mechanism similar to a recording temperature thermometer in the respect that it has any well known type of clock mechanism or other means with a spindle 67 operated by the mechanism at a uniform rate of speed and adapted to have a dial 68 mounted thereon 5 to rotate therewith. A stylus 69 is pivoted at 70 so as to mark upon the face of the dial 68 as the latter is rotated and is connected by a flexible cable 71 to the stack of lumber in the drying compartment, suitable pulleys 10 or sheaves 72 being arranged to carry the cable to the desired point of attachment to the stack of lumber. A weight 73 is attached to the outer end of the cable 71 to maintain same at a tension and the cable passes 15 through a sleeve 74 which may be adjustably secured thereto by the thumb screw 75. This sleeve 74 has a pivot pin 76 extending therefrom through the lever 69 to permit the necessary freedom of movement of the lever 20 25 69 as the cable 71 is moved by the expansion and the contraction of the lumber. The dial 68 has a neutral line 77 marked thereon and the marking at one side of the neutral line by the stylus serves to indicate the expansion 30 of the lumber during the steaming operation and the marking at the opposite side of the neutral line, the contraction during the drying operation.

In using this drier, the lumber is stacked 35 on the truck 6 in any suitable manner which will permit the steam and heat penetrating to all parts of the stack and permit circulation of air therethrough, the floor of the truck being preferably constructed as an 40 open frame which permits the steam and heated air passing upwardly directly therethrough into contact with the lumber stacked thereon. This truck after loading is run into the drier compartment on the tracks 45 5 and 7 after which the door 21 is closed to seal up the drier compartment. When the truck load of lumber is located in the proper position the end of the cord or cable 71 is attached to a piece of lumber on the pile 50 near the top and the weight 73 at the end of the cable 71 holds the cable at a tension. The stylus 69 is then adjusted at the neutral line 77.

The valves 28 in the stacks 25 are then 55 closed and the valves 52 in the side draft chambers 84 opened and the doors 50 at the ends of the air passageways 47 closed. The valve 88 is opened so as to admit steam to the steam pipes 59 which is emitted through 60 the apertures thereof and circulates up through the stack of the lumber on the truck 6. The amount of steam admitted after the valve 88 is opened is automatically 65 regulated by the temperature in the drier compartment, by the fluid in the bulb 91

which acts upon the automatic valve 89 to maintain a uniform temperature in the drier compartment. The valves 17 of the air inlets to the air space 10 of the side walls are opened during this operation so as to afford 70 a cooling effect on the inner sections of the side walls and this cooling effect of the side walls induces a down draft along the side walls which causes the air, after it rises up through the stack of lumber, to circulate 75 downwardly at each side of the compartment and enter the side draft openings 84 from which it is drawn through the pipes 51 to the passageways 47 at the bottom of the pit 3, from which it escapes through the 80 apertures 49 and circulates with the steam from the jet pipes 59, up through the lumber again. As the steaming operation continues the lumber becomes saturated and expands and the expansion of the stack of 85 lumber is communicated through the cable 71 to the stylus 69 of the recording instrument which moves outwardly away from the neutral line 77 until the lumber is completely 90 saturated, at which time the stylus 69 marks a line outside and parallel with the neutral line 77. When the stylus marks such a line it is evident that the lumber is thoroughly saturated and time for the steaming operation to be discontinued. The valve 88 is 95 then closed and the valves 52 in the side draft passageways likewise closed to prevent recirculation of the air, and the valve 85 opened so as to admit steam to the heating coils 62 and 65. The valves 28 in the stacks 100 25 are also opened and the ventilation through the stacks then controlled entirely by the automatic valves 31 and 32. The doors 50 controlling the supply of fresh air are opened so as to admit air into the passageways 47 which passes up through the perforated top plates 49 and through the heating coils 62 and 65 and then up through the stack of lumber on the truck 6. The valves 17 controlling admission of air to air 105 space 10 in the side walls remains open during the drying operation so as to cool the interior surfaces of the side walls sufficiently to enforce a down draft along the side walls and the air thus passing downwardly enters 110 the side draft passageways 84 through the air space 24. The circulation of air is regulated not only by the cooling of the side walls of the drier but also by the automatic dampers 31 and 32 which act to maintain a 115 uniform circulation of air regardless of the temperature inside and outside the drier compartment. Assuming that the controlling element 34 is adapted to operate between 0° F. and 100° F., the valve 32 will 120 be entirely open at an outside temperature of 100° and gradually close as the outside temperature decreases so that said valve will be entirely closed at 0° F. Thus a low temperature outside the drying compartment 125 130

which would tend to increase the draft in the flues 25 reduces the area of the passageway so that the volume of air passing through the stack is diminished and the circulation or draft through the drier compartment kept uniform notwithstanding variations of outside temperature.

The thermostatic element 35 serves the same purpose in connection with changes of temperature inside the drier compartment and is arranged, for example, to operate between the temperatures of 100° F. and 200° F. At 100° F. the valve 31 is entirely open and said valve gradually closes as the temperature in the drying compartment increases up to 200° at which point the valve 31 is closed. Thus a high degree of heat in the drier compartment which would tend to increase the circulation therefrom through the stacks 25 effects a suitable closing of the valve 31 so that the volume of air exhausted is constant, notwithstanding the variation in the draft.

From the foregoing it will be observed that if the temperature inside and outside the compartment is nearly 100° and there is, therefore, little difference in temperature to effect draft through the stacks 25, the valves 31 and 32 will be entirely open so as to permit free draft circulation to take place and as the difference in the inside and outside temperatures become greater and tends to enforce a greater degree of draft, through the stacks 25, the valves 31 and 32 are automatically adjusted so that the volume of air withdrawn from the drier compartment is substantially constant and the drying may, therefore, be effected at a uniform rate which will accomplish most satisfactory results in drying the lumber.

As the drying operation is carried on the natural moisture in the lumber and the moisture absorbed thereby in the steaming operation, is gradually extracted by the circulating heated air and the stack of lumber, therefore, contracts. As the lumber thus contracts, the stylus 69 moves inwardly from the extreme outward position assumed at the time of steaming the lumber and crosses the neutral line 77 to the inner side thereof. When the stack of lumber becomes thoroughly dry the stylus 69 discontinues moving inwardly and marks a line on the revolving record sheet 68 parallel with the neutral line 77 and thus indicates that the drying operation is completed. The truck load of lumber is then withdrawn from the drying compartment after which the steaming and drying operation is repeated on another truck load of lumber in the same manner.

The air spaces 10 in the side walls are intended to cool the inside surfaces of the side walls so that the air rising at the center of the drying compartment is drawn laterally toward each side and down along the side

walls to the side draft passageways 84, and the cooling effect on the walls may be controlled by adjusting the valves 17 in accordance with the outside temperature to secure the desired rate of circulation in the drying compartment.

While I have shown and described my invention in a particular form, I am aware that various changes and modifications may be made without departing from the principles of my invention and I, therefore, do not propose limiting the patent granted hereon otherwise than necessitated by the prior art.

I claim as my invention:

1. In a drying kiln, the combination of an enclosure for the material to be dried, having heating means at the bottom for creating air circulation upwardly through the enclosure, outlets from the enclosure at each side near the bottom thereof, and means at opposite sides of the enclosure for enforcing downward circulation of air within the enclosure along each side wall to said outlets.

2. In a drying kiln, the combination of an enclosure for the material to be dried, heating means at the bottom of the enclosure, walls at each side of the enclosure, each comprising spaced sections with an air chamber therebetween, and having a draft outlet at the top of the air chamber and an air inlet thereto at the bottom, said air chambers being adapted to afford circulation through the walls for cooling the inner surfaces thereof, to enforce down draft in the enclosure adjacent each of the side walls, and valve-controlled ducts for conducting and distributing the downwardly directed air under the heating means.

3. In a drying kiln, the combination of an enclosure for the material to be dried having a draft passageway extending along each side wall of the kiln near the bottom thereof, restricted air inlet means extending throughout the length of the passageway to admit air thereto from the enclosure, and means for optionally exhausting the air from said draft passageways to the exterior of the enclosure, or returning same to the enclosure.

4. In a drying kiln, the combination of an enclosure having the lateral walls thereof provided with air spaces, means for admitting air into the air spaces at the bottom of the wall and exhausting the air therefrom at the top so as to cool the interior surface of the wall and enforce down draft in the enclosure adjacent each of the side walls, a duct extending along each side wall and adapted to admit the air flowing downwardly along the side walls thereinto, and an exhaust stack communicating with each of said ducts to withdraw the air therefrom.

5. In a drying kiln, the combination of an enclosure having heating means at the bot-

- tom, an air passageway under the heating means leading from the exterior of the enclosure for admitting air into the enclosure below the heating means, a duct extending 5 along each side wall adjacent the bottom thereof and adapted to admit air thereinto from the enclosure, and a stack communicating with each duct to exhaust the air therefrom to the exterior of the enclosure.
- 10 6. In a drying kiln, the combination of an enclosure for the material to be dried, selectively operable steaming and heating means at the bottom of the enclosure, an air duct having an inlet from the enclosure at 15 the side of and near the bottom of the enclosure, and means for optionally recirculating the air from said duct through the steaming and heating means or withdrawing the air to the exterior of the enclosure.
- 20 7. In a drying kiln, the combination of an enclosure for the material to be dried, having selectively operable steaming and heating means at the bottom thereof and exhaust ducts extending lengthwise thereof the side 25 walls adjacent the bottom thereof adapted to deliver air under the heating and steaming means, outlets from the enclosure leading into the ducts near the bottom of the enclosure, and valves for selectively exhausting 30 the air from the side ducts to the exterior of the enclosure or returning the air through the heating and steaming means into the enclosure.
8. In a drying kiln, the combination of an 35 enclosure for the material to be dried, having a side wall with an air space therein for cooling the inner surface of the wall so as to enforce circulation in the enclosure, means in the air space near the bottom there- 40 of for effecting uniform distribution of air throughout the length of the wall, and an air inlet leading into the air space below said means and having an adjustable door for controlling the admission of air.
- 45 9. In a drying kiln, the combination of an enclosure for the material to be dried, means for heating the material therein, a by-pass for conducting air to the heating means from the point in the enclosure at a distance 50 from the heating means so as to recirculate the air in the enclosure, a draft outlet from the by-pass to the exterior of the enclosure and automatically adjustable means for regulating the draft outlet.
- 55 10. In a drying kiln, the combination of an enclosure for the material to be dried, means for heating the material therein, a by-pass for conducting air to the heating means from a point in the enclosure at a distance 60 from the heating means so as to recirculate the air in the enclosure, a draft outlet from the by-pass leading to the exterior of the enclosure and thermostatically operated means for automatically controlling the 65 draft outlet.
11. In a drying kiln, the combination of an enclosure for the material to be dried, means for heating the interior of the enclosure, a by-pass for conducting air to the heating means from a point in the enclosure 70 at a distance from the heating means so as to recirculate the air in the enclosure, a draft outlet from the by-pass leading to the exterior of the enclosure and means automatically controlled by the temperature inside and outside the enclosure for regulating the draft outlet.
12. In a drying kiln, the combination of an enclosure for the material to be dried, means for heating the enclosure, a by-pass for conducting air to the heating means from a point in the enclosure at a distance from the heating means so as to recirculate the air in the enclosure, a draft outlet from the by-pass leading to the exterior of the enclosure and means automatically regulated by the difference in temperature inside and outside the enclosure for regulating the draft through the outlet.
13. In a drying kiln, the combination of an enclosure in which the material is dried, heating means for the enclosure, a draft outlet therefrom, a valve comprising two sections co-operable to control the draft through the outlet and means for independently controlling each valve section respectively, by the temperature inside the enclosure and the temperature outside the enclosure.
14. In a drying kiln, the combination of an enclosure having heating means adapted to create air circulation centrally up through the enclosure, side walls provided with cooling means for affording a down draft in the enclosure along the side walls, a draft 105 passageway along the base of each side wall, an outlet from each passageway to the exterior of the enclosure and thermostatically controlled means for regulating the exhaust through said outlets.
15. In a drying kiln, the combination of an enclosure having means for heating the interior of the enclosure and thermostatically operated means controlled by the temperature in the enclosure for regulating the heating means, and thermostatically operated means for controlling the exhaust of air from the enclosure.
16. In a drying kiln, the combination of an enclosure for the material to be dried, independently operable heating and steaming means in the enclosure, and thermostatically operated means controlled by the temperature within the enclosure for regulating the operation of the heating and steaming 120 means, and thermostatically operated means for controlling the exhaust of air from the enclosure.
17. In a drying kiln, the combination of an enclosure for the material to be dried,

- and an indicator automatically operable by the expansion and contraction of the material which is being dried in the enclosure.
18. In a drying kiln, the combination of an enclosure for the material to be dried, means adapted to be connected with the material in the enclosure so as to be operable by the expansion and contraction of the material and an indicator at the exterior of the enclosure operated by said means.
19. In a drying kiln, the combination of an enclosure for the material to be dried, a recording dial adapted to have movement imparted thereto and a marker operated on said dial and adapted to be connected with the material in the enclosure so as to indicate on the dial the expansion or contraction of the material.
20. The improvement in the art of kiln drying lumber which consists in recirculating air through the lumber in the kiln chamber by withdrawing air from the chamber and returning the same thereto and at the same time mixing steam with the returned air and thereafter interrupting the recirculation of air and permanently withdrawing air from the chamber and supplying fresh air in place thereof.
21. A kiln for steaming and drying lumber, comprising an enclosure for the lumber, selectively operable heating and steaming means at the bottom of the enclosure for inducing a natural draft circulation of air upward through the lumber, exhaust ducts for withdrawing air from the enclosure adjacent the lower portion of its side wall, and having valve-controlled means for selectively delivering the air to the exterior of the enclosure or returning the same to the heating and steaming means for recirculation through the enclosure, and valve-controlled means for admitting external air to the heating and steaming means.
22. A kiln for steaming and drying lumber, comprising an enclosure for the lumber, selectively operable heating and steaming means at the bottom of the enclosure, and a cooled side wall for inducing a natural draft upwardly through the lumber and downwardly along the side wall.
23. A kiln for steaming and drying lumber, comprising an enclosure for the lumber, selectively operable heating and steaming means at the bottom of the enclosure for inducing a natural draft circulation of air upward through the lumber, an exhaust stack, exhaust ducts for withdrawing the air from the enclosure adjacent the lower portion of said side wall and having valve-controlled means for selectively delivering the air to said stack or returning the same to the enclosure.
24. In a drying kiln, the combination of an enclosure for the material to be dried, having heating means at the bottom thereof, comprising laterally spaced inclined series of coils collectively joined to a single source of supply, said coils being arranged to evenly distribute the heat from the coils crosswise and longitudinally of the enclosure at low or high temperatures.
25. In a drying kiln, the combination of an enclosure for the material to be dried, having steam-spraying means near the bottom thereof, comprising horizontal perforated pipes reversely extending from supply pipes and connected to the latter so as to project therefrom angularly in the direction of the flow of steam in the supply pipes and extend crosswise and longitudinally of the enclosure, means for maintaining an even volume of steam at all the jets irrespective of their distance from the source of steam supply, and means for draining condensation from the spraying means.

BENJAMIN D. CURTIS.
